ANODE CONSTRUCTION FOR DISCHARGE
TUBES HAVING ROTARY ANODESGottfried Bruno Jonas, Eindhoven, Netherlands,
assignor to C. H. F. Müller Aktiengesellschaft,
Hamburg, GermanyApplication February 19, 1934, Serial No. 712,027
In Germany March 16, 1933

7 Claims. (Cl. 250—35)

My present invention relates to anode constructions for discharge tubes having rotary anodes, and more particularly to X-ray tubes having such anodes.

5 My invention is a continuation in part of my copending application Ser. No. 497,860, filed November 24, 1930, now U. S. Patent No. 1,984,583.

To dissipate the heat caused by electron bombardment at the anode, the anode is usually made of a metal of high heat conductivity, for instance of copper. However, as copper—on account of its low melting point—is not well suited to form the target surface of the anode—i. e. the surface upon which the electrons impinge—an insert of a metal of higher melting point, as a rule tungsten, is used as the target.

It has been found that the target-surface of an X-ray tube after it has been in operation for some time, becomes more or less damaged, shows gradually fissures, and finally scales off, which impairs the usefulness of the tube.

In my Patent #1,927,456 and my above referred to Patent #1,984,583, I have described anode constructions in which by subdividing the target surface by seams or otherwise, and suitably embedding it in the adjoining copper surface of the anode, damaging of the target surface is avoided.

According to one feature of my present invention the target surface consists of a thin insert or cap member of tungsten or similar refractory material, which is in intimate contact with the copper of the anode, the target surface being provided with radial laminations. In case the target is conical, which is usually the case in such anodes, the lamination is along generatrices of this cone.

According to a further feature of my invention the target is sub-divided by radially extending grooves converging towards the apex of the cone, the target assuming the shape of a spur gear or conical wheel. Such a construction has the advantage of increasing the area which is subjected to electron bombardment, without reducing the sharpness of the focus.

In such an arrangement the X-ray beam emitted by the anode forms an acute angle with the length direction of the grooves. The grooves are preferably narrow, for instance, having an average width of 0.2 to 2 mm. so that the focus overlaps 1 to 10 grooves.

In order that the invention may be more readily understood and carried into effect, it will be explained more fully with reference to the accompanying drawing, in which:

Figure 1 is a schematic bottom view of the target of an anode made according to my invention.

Fig. 2 is a similar view of a modification, shown for the purpose of illustrating certain advantages 5 of the construction of Fig. 1.

Fig. 3 is a schematic side view of an X-ray tube having an anode according to my invention.

Fig. 4 is a partly sectionized perspective view of a portion of an anode made in accordance 10 with the invention.

Referring to Fig. 3, the X-ray tube represents an X-ray tube having a rotary anode, of the general type described in the U. S. patent to A. Bouwers No. 1,893,759, and comprises an envelope having tubular glass portions 1 and 1', an intermediate metal sleeve 2, which preferably consists of chrome iron, said sleeve being sealed to the ends of the glass portions 1 and 1'.

The metal sleeve 2 is provided with a ray-emitting window 12 through which the active X-rays can emerge from the tube.

The anode or anti-cathode 21, which will be discussed more fully later on, consists of a tubular copper member 22 having a conical end 25 carrying a conical tungsten target 23, the apex of which is preferably cut off, as shown at 20.

The anode member 22 surrounds a cylinder 1 of ferro-magnetic material, for instance of iron. The anode is rotatably supported on a stem 5 sealed to the re-entrant portion of the glass cylinder 1, suitable bearings 6 being interposed between the stem 5 and the anode proper.

Opposite to the anode is disposed an incandescent cathode 4 surrounded by a slotted focusing device 13, which is sealed to the re-entrant portion of the glass cylinder 1'.

The anode constitutes the rotor of an induction motor the stator of which consists of a magnet system 9 and of a stator winding 11, and is surrounded by a housing 10, which is secured to the metallic portion 2 of the envelope.

When the motor is connected to a suitable electrical supply source the anti-cathode is rotated. Such arrangement as is well known permits a very high loading of the tube.

Referring to the anode construction, the tungsten target 23 consists of a comparatively thin tungsten insert or cap member, which may be formed, for instance, by pleating or stamping a tungsten sheet in the form of a grooved conical disc having the shape of a spur-gear and securing the target to a similarly conical end face of the copper anode. Or the copper may be cast on the rear side of the tungsten disc.

As shown in Fig. 4, the target is formed of a thin sheet 24 of refractory material, for instance tungsten, which is provided by pleating or corrugating with radially-extending serrations 25.

- 5 5 The serrated sheet 24 is secured to a backing member 26 of good heat-conducting material, for instance cast copper, which member is provided with grooves corresponding to the serrations 25. The sheet 24 has been broken away at 10 27 to more clearly show the construction.

While the rear surface of the tungsten target and the corresponding surface of the copper may be smooth, I prefer to make them grooved, as above stated. In any case a very intimate contact between the tungsten and the copper is to be provided.

As will appear, by grooving the active surface of the target, thus the surface upon which the electrons impinge this surface is further increased; this, however, does not reduce the sharpness of the focal spot. As appears from the drawing, the X-ray beam forms an acute angle with the length direction of the grooves.

Preferably one to ten grooves are provided per 25 focus width. Such a target combines the advantage of distributing the energy over a large surface with that of a great resistance against fissures and scaling off.

Such target construction has also the advantage of very easy and cheap manufacture, as the tungsten target can be conveniently stamped or pleated from a thin tungsten sheet.

It would first seem that the grooving of the target would give rise to considerable temperature differences between its different portions. Such would happen if such grooves were applied to an anode of the stationary type, especially if the relative differences in thickness of the target were considerable. However, I have found 40 that in the case of a rotary anode, especially with a thin tungsten target made according to my invention, the temperature differences between the hills and dales and other portions of the grooves is negligible.

45 I have also found that a parallel grooving as shown in Fig. 2 would have the drawback that the shape of the focus continuously changes during operation, as such a target surface is not symmetrical with respect to the cathode. This drawback is evidently absent with an arrangement as shown in Figs. 1 and 3.

While I have described my invention in connection with specific examples and in a specific application, I do not wish to be limited to same, but desire the appended claims to be construed as broadly as permissible in view of the prior art.

What I claim is:

1. In an X-ray tube of the rotary anode type,

an anode comprising a cylindrical anode body of copper, and a target consisting of a radially pleated thin tungsten sheet, said copper body having a grooved end face conforming to the rear face of said target, said target being secured to said copper body and being in intimate contact therewith.

2. In an X-ray tube of the rotary anode type, an anode comprising a cylindrical body of a metal of good heat conductivity and having a substantially conical end-face grooved along generatrices of the cone, a conical cap-member of thin highly-refractory material of uniform thickness, said cap member covering said end face and being provided with grooves engaging the grooves of said end-face, the average width of the grooves being between .2 and 2 mm.

3. In an X-ray tube of the rotary anode type, an anode comprising a body of a metal of good heat conductivity, a conical end-member of highly refractory material provided on the inner end of said body, said conical end-member being provided over its entire active surface with grooves extending along its generatrices and the grooves being of such average width that the focal spot overlaps a plurality of grooves.

4. In an X-ray tube of the rotary anode type, an anode comprising a cylindrical body of a good heat-conducting metal, said body having a substantially conical end-face grooved in the direction of its generatrices, and a corrugated conical cap-member of thin refractory material, the corrugations of said cap-member fitting into the grooves of said end-face.

5. An X-ray tube comprising an evacuated envelope, an anode structure, and a cathode structure, said anode structure comprising a rotatable body opposing the cathode with a surface of revolution for the formation of a focal spot, said surface being provided with contiguous grooves extending along the generatrices of the surface.

6. An X-ray tube comprising an evacuated envelope, a rotatable anode, and an electron-emitting incandescent cathode, said anode opposing said cathode with a conically-shaped surface, said surface being provided with contiguous grooves extending along the elements thereof.

7. An X-ray tube comprising an evacuated envelope, an anode structure, and a cathode structure, said anode structure comprising a rotatable body having an axis of rotation coinciding with the axis of said tube and opposing said cathode structure with a surface of revolution, said surface being provided with grooves having inclined walls and extending in a direction from the axis of rotation to the periphery, said grooves having an average width between .2 and 2 millimeters.

GOTTFRIED BRUNO JONAS.
